UNITED STATES PATENT OFFICE.

GEORGE KELLY, OF HINSDALE, ILLINOIS.

INSULATING MATERIAL AND METHOD OF MANUFACTURING SAME.

No. 844,139.

Specification of Letters Patent.

Patented Feb. 12, 1907.

Application filed April 24, 1906. Serial No. 313,427.

To all whom it may concern:

Be it known that I, GEORGE KELLY, a citizen of the United States, residing at Hinsdale, in the county of Dupage and State of Illinois, have invented a new and useful Insulating Material and Method of Manufacturing Same, of which the following is a specification.

This invention relates to the method of manufacturing insulating material and the like, as well as the article produced by such method.

The principal object is to produce a highly-efficient insulating article from printed-paper stock, which can now be purchased at very small cost compared to the cost of unprinted paper, even of the same grade. The invention is primarily based on the discovery that the inks employed in printing contain ingredients which can be softened and made to flow in order to coat as a binder and vulcanizing agent in cementing the sheets together and hardening the same to produce an article highly efficient as an insulator, said article being fire and damp proof and capable of withstanding high mechanical stress or strain.

In carrying out the invention sheets of printed matter—such as newspapers, magazines, and other periodicals, posters, bills, and the like—comprising paper sheets having printers' inks and colors thereon, are thoroughly moistened with a vulcanizing liquid. This liquid may perhaps be composed of a variety of ingredients; but that which so far discovered has given the greatest satisfaction in actual practice is a composition set forth in a copending application and comprising liquid glass, preferably silicate of sodium in liquid form, white lead, sulfur, and rubber. Ninety-five parts of silicate of sodium are employed with about five parts of flowers of sulfur, ten to fifteen parts of rubber, and five parts of white lead. These ingredients are measured by weight and are thoroughly intermixed in any well-known manner, so that they form an even and perfect mixture. The white lead, however, is not essential and may or may not be employed, as desired.

50 The vulcanizing compound may be applied to the sheets in a variety of ways—as, for instance, by brushing said sheets therewith or by dipping the sheets into the compound and

afterward placing them one upon the other to form a body. The dipping method is perhaps preferable and may be accomplished in the following manner, reference being had to the accompanying drawings, wherein the different steps are disclosed in a diagrammatic manner.

Figure 1 of said drawings is a sectional view showing the first step. Fig. 2 illustrates the draining of the body; Fig. 3, the preliminary drying or setting of the same; Fig. 4, the pressing operation, and Fig. 5 the vulcanizing step.

A vessel, as 10, having a perforate bottom, is partially submerged in a body 11 of the liquid compound, and the sheets are piled one upon the other in the vessel, being thus successively submerged and impregnated with the compound. When the body of sheets 12 of the desired thickness has been made, the vessel is elevated from the liquid, as shown in Fig. 2, and the surplus allowed to drain therefrom. The body 12 of saturated sheets is then placed upon a screen, as 13 in Fig. 3, and the composition allowed to partially dry or set, after which said body 12 is pressed by any suitable means, (illustrated diagrammatically at 14 in Fig. 4.) After the pressing operation the compacted body 12 is placed in a vulcanizing-press (shown diagrammatically at 15 in Fig. 5) and is vulcanized under pressure and moderate heat.

The resultant sheet is an electrical insulator slab, board, or the like having a very high degree of efficiency, samples having withstood a test of fifteen thousand volts without breaking down. A further and important feature is that the resultant product is both fire and moisture proof and is capable of withstanding high mechanical strain, so that the continued use will not affect its efficiency. This is an exceedingly important feature, for experience has demonstrated that all vulcanized fiber board with which I am acquainted in time absorbs moisture, which seriously impairs its efficiency. The use of printed sheets is important, for all inks used are practically vulcanizing agents. These inks include varnishes, shellac, various kinds of pitches, asphaltum, mucilages, soaps, and various sulfurs, sulfite of iron and copper, different kinds of oils, and the like, so

- that it will be apparent that all these ingredients, as well as the coloring agents, which include chalk and clay, are made use of in the composition and nothing is wasted.
- 5 It is found that the alkali of the silicate of sodium softens or frees these desired ingredients to permit them to act as vulcanizing agents. Furthermore, the said silicate of sodium makes the articles fireproof, and thus 10 performs a double function. The employment of sheets of paper is advantageous, inasmuch as the sheets of ordinary newspapers are of substantially the same size and are uniform in thickness. Therefore if these 15 sheets are spread out flat and laid one upon the other they will form a comparatively large board. If doubled, a board of a different size is made and there is no necessity of cutting the material. While the article is 20 capable of other uses than insulating purposes, it is highly efficient for the latter, not only for the reasons set forth, but also because it is not frangible or liable to crack and can then be successfully employed about 25 dynamos and electrical machinery, as it is not deleteriously affected by the jars and vibrations thereof. It is moreover capable of a high polish, so that it may be made very ornamental.
- 30 Having thus fully described my invention, what I claim as new, and desire to secure by Letters Patent, is—
1. That improvement in the process of manufacturing insulating articles, which consists in impregnating material having printers' ink thereon with a vulcanizing-binder, and vulcanizing the composition.
  2. That improvement in the process of manufacturing insulating articles, which consists in impregnating printed sheets with a binder that frees the inks in said sheets, and afterward vulcanizing the sheets.
  3. That improvement in the process of manufacturing insulating articles, which consists in impregnating paper sheets having printers' ink thereon with a vulcanizing-binder, and then vulcanizing the same.
  4. That improvement in the process of manufacturing insulating articles, which consists in pressing and vulcanizing a body of material having printers' ink thereon and impregnated with a vulcanizing-binder.
  5. That improvement in the process of manufacturing insulating articles, which consists in pressing and vulcanizing a body of printed sheets that is impregnated with a binder which acts on the print in said sheets.
  6. That improvement in the process of manufacturing insulating articles, which consists in producing a body of layers of superposed sheets having printers' ink thereon and that is impregnated with a vulcanizing-binder, and pressing and vulcanizing the body.
  7. That improvement in the process of manufacturing insulating articles, which consists in producing a body of printed material having an alkali incorporated therein, and pressing and vulcanizing the body.
  8. That improvement in the process of manufacturing insulating articles, which consists in producing a body of printed material having a vulcanizing agent and an alkali incorporated therein, and pressing and vulcanizing said body.
  9. That improvement in the process of manufacturing insulating articles, which consists in moistening sheets, having printers' ink thereon, with vulcanizing material that includes a vulcanizing agent and an alkali, forming said sheets into a body, and pressing and vulcanizing the body.
  10. That improvement in the process of manufacturing insulating articles, which consists in forming a body of printed material having incorporated therein a vulcanizing material that includes rubber and liquid glass, and pressing and vulcanizing the body.
  11. That improvement in the process of manufacturing insulating articles, which consists in moistening sheets of printed material with a vulcanizing material that includes rubber and liquid glass, forming said sheets into a body, and pressing and vulcanizing the body.
  12. That improvement in the process of manufacturing insulating articles, which consists in laying printed sheets one upon the other in a vulcanizing compound, removing the body of sheets from the compound, and vulcanizing the same.
  13. That improvement in the process of manufacturing insulating articles, which consists in impregnating sheets with a compound comprising liquid glass, rubber and sulfur, forming the sheets into a body, pressing the body, and finally vulcanizing the same.
  14. As an article of manufacture, a body comprising a vulcanized composition of matter having printers' ink thereon, and a binder.
  15. As an article of manufacture, a vulcanized body, comprising layers of sheets having printers' ink thereon, and a vulcanizing-binder.
  16. As an article of manufacture, a vulcanized body, comprising layers of printed sheets, and a vulcanizing-binder, including an alkali.
  17. As an article of manufacture, a vulcanized body comprising layers of printed sheets, and a vulcanizing-binder comprising rubber and liquid glass.
  18. As an article of manufacture, a vulcanized body comprising layers of printed sheets, and a vulcanizing-binder comprising sulfur, rubber and liquid glass.
  19. That improvement in the process of manufacturing insulating articles, which con-

sists in impregnating material having printers' ink thereon, with a vulcanizing-binder.

20. That improvement in the process of manufacturing insulating articles, which consists in impregnating material having printers' ink thereon, with a vulcanizing-binder that frees and becomes incorporated with the materials of said ink.

In testimony that I claim the foregoing as my own I have hereto affixed my signature in the presence of two witnesses.

GEORGE KELLY.
